United States Patent Office

Des. 189,053
Patented Oct. 18, 1960

189,053

CANDLEHOLDER

Orville C. Hamon, Cedars, Okla.
(P.O. Box 813, Fort Smith, Ark.)

Filed Feb. 24, 1960, Ser. No. 59,492

Term of patent 14 years

(Cl. D48—2)

I claim:

The ornamental design for candleholder, as shown.
